Attorney

UNITED STATES PATENT OFFICE.

JESSE B. HINTHORN, OF HIAWATHA, KANSAS.

SHADE-TRIMMER.

SPECIFICATION forming part of Letters Patent No. 606,548, dated June 28, 1898.

Application filed August 26, 1897. Serial No. 649,614. (No model.)

To all whom it may concern:

Be it known that I, JESSE B. HINTHORN, a citizen of the United States, residing at Hiawatha, in the county of Brown and State of Kansas, have invented certain new and useful improvements in Shade-Trimmers; and I do hereby declare the following to be a full, clear, and exact description of the invention, such as will enable others skilled in the art to which it appertains to make and use the same.

My invention relates to new and useful improvements in machines for trimming curtains; and it has for its object, primarily, to provide a machine of this character with which the edges of a curtain can be uniformly and smoothly trimmed and one which will be especially simple in construction, durable, economical, and reliable in use.

With these and other objects in view, which will become apparent in the course of the following description, all looking toward simplifying and improving devices of this character generally, my invention consists in the novel combination and arrangement of parts which will be hereinafter fully described, and the points of novelty will be particularly pointed out in the appended claims.

I am enabled to accomplish the objects of my invention by the simple means illustrated in the accompanying drawings, in which—

Figure 1 is a perspective view of my improved device. Fig. 2 is a transverse section showing a curtain in position to be trimmed in dotted lines, and Fig. 3 is a detail perspective view of the knife-carrying blocks.

Referring to the drawings, the numeral 1 indicates two end pieces which are connected by a base-piece 2 and longitudinal strips 3 and 4. The strips 3 and 4, as shown in the drawings, are secured to the upper edges of the end and suitably spaced apart to form a longitudinal slot 5, through which extend two inclined knives 6, carried by blocks 7, provided with tongues 8, extending into longitudinal grooves 9, formed near the lower end of a depending member 10. Said member is provided with a longitudinal slot 11, extending throughout the entire length thereof, for the passage of set-screws 13, one of which is secured to the rear side of each knife-carrying block for the obvious purpose of adjusting the blocks laterally with relation to each

other. The numeral 14 indicates a knife-guard having arms 15 secured to either end thereof and extending from the side pieces, 55 to which pieces said arms are pivoted, as indicated by the numeral 16.

At the extreme front edge of the base-piece I provide an inclined longitudinal strip 17, which extends parallel with a strip 18, and 60 between said strips I provide two sliding brackets 19, perforated in their upper portions, as indicated by the numeral 20. Secured to the front edge of the base, about midway of the length thereof, is a keeper 22, 65 in which is adapted to slide a wedge 23, by which means the strip 17 is caused to move inwardly and outwardly to maintain the brackets in adjusted position or permit them to be slid to any desired point. 70

The strip 17 is removable and forms part of the track upon which the brackets 19 have movement, said strip being tightened or regulated by the wedge 23. The strip 17 assists in supporting the brackets and is applied 75 against the outer portion of the latter, the wedge 23 being sufficiently long to hold the said strip in position, and of course the degree of tightness of bearing of the said strip against the outer portions of the brackets will 80 depend upon the force with which the wedge is driven into the keeper 22.

I preferably provide upon the front edge of the strip 4 a depending member 24, having a rounded upper edge 25, over which the curtain passes during the operation of trimming the same. 85

The numeral 26 designates a rule or measure which I provide upon the rear edge of the strip 3 for the obvious purpose of obtaining 90 the amount of material to be trimmed from the edges of the curtain.

In operation the curtain as it comes from the factory is unrolled until the wooden rod secured to one end thereof is exposed, and 95 the same is sawed to the desired length and the knife-guard is rocked upwardly and the rod carried under the same. The brass rod 27 is then removed and inserted through the hole in the central portion of the curtain, and 100 the rod is then replaced in the brackets and said brackets properly adjusted. The width or the amount of material to be trimmed from the curtain is then ascertained and the knives

are properly adjusted. When the curtain-roll is grasped and pulled toward the rear of the machine, it is obvious the knives will trim the desired amount of material from the edges 5 of the curtain.

It is obvious that the invention herein set forth is susceptible to minor changes and modifications involving mechanical skill, which may be made within the scope of the 10 invention without departing from the spirit thereof, and I do not, therefore, desire to limit myself to the precise construction shown.

Having thus described my invention, what I claim as new, and desire to secure by Letters 15 Patent, is—

1. A device of the character described comprising a suitable frame slotted in the direction of its length, laterally-adjustable knives extending through said slot, a knife-guard 20 pivoted to said frame and adapted to be rocked upon the knives for the purpose set forth, suitably-guided laterally-adjustable brackets perforated for the reception of a rod, said rod being adapted to enter the curtain-roll, means 25 for securing the knives at any desired point throughout the length of the machine, and means for similarly securing the laterally-adjustable brackets, substantially as described.

2. A device of the character described composed of end pieces, a suitable base secured to said end pieces, strips secured to the end pieces above the base and suitably spaced apart to form a longitudinal slot, a depending member secured to the rear strip and provided with a slot and a groove therein, blocks 30 carrying knives extending through the slot, said blocks being provided with lugs or projections extending into said groove, set-screws or their equivalents passing through the slot 35 in the depending member and into the knife- 40

carrying blocks, whereby said blocks are held in adjusted position, a knife-guard pivoted to the frame and adapted to be rocked upon the knives, laterally-adjustable brackets suitably guided at one side of the machine, a rod 45 extending between said brackets, and means for adjustably securing said brackets, substantially as described.

3. The herein-described device comprising a suitable base and suitable end pieces secured to said base, strips secured to the end pieces and suitably spaced apart to form a slot, the member depending from one of the strips adjacent to the slot, said member being provided with a longitudinal slot and a 50 groove, laterally-adjustable knife-carrying blocks having knives extending through the slot in the top strip, said blocks being provided with set-screws or their equivalents passing through the slot in the depending 55 member and lugs or projections extending into the groove in said member, a knife-guard pivoted to the end pieces and adapted to be rocked upon the knives, parallel strips at the front edge of the machine, brackets maintained and guided between said strips, said brackets being perforated for the reception of the rod, a keeper secured to the front edge 60 of the machine and having the wedge therein adapted to be operated to move the outer 70 strip against the bracket to maintain the same in adjusted position or permit it to be moved, substantially as described.

In testimony whereof I have signed this specification in the presence of two subscribing witnesses.

JESSE B. HINTHORN.
